STOP PAD FOR WIND INSTRUMENTS

James A. Collis, Los Angeles, Calif.

Application December 19, 1945, Serial No. 635,858

4 Claims. (Cl. 84—385.1)

1

This invention relates to musical instruments and more specifically to pads for the stops of wind instruments, such for example, as, saxophones, clarinets, and the like.

The composition of stop pads has been wide and varied, featuring numerous materials and combinations of material, but the substance most often used has been a felt base with a surface of water-proof material such as fish skin, wax paper or leather. Often the pads are objectionable because of their rapid deterioration under the influence of breath condensate but equally important has been their failure to provide an adequate closure without undue absorption of resonance from the musical instrument, particularly if the external surfaces of the instrument surrounding the stop apertures have been worn unevenly. Application of the conventional pad to the key cavity almost always requires the skill of competent workmen in the art. Imperfect stopping interferes with proper operation of the instrument and detracts from the tone quality. A pad which will operate more effectively or over a relatively longer period of time is therefore greatly to be desired.

In the present state of the art of pad development and wind instrumentation, care of the stops requires a greater amount of attention of the musician than any other part of the instrument, and the pads themselves require frequent replacement.

In addition to the requirement of durability and adaptability, maximum tone quality and undamaged resonance dictates that the pads be provided with a smooth, substantially hardened, yet flexible surface. It is intended that the pad, which is the object of this invention, incorporate these desirable features and that of easy adaptability so that replacement be made by the musician himself. Thus, by utilizing a thermoplastic agent of one of the well known varieties within the key cavities, the pad may be caused to adhere therein with the aid of mild applied heat such as that produced from a match. By the same token, the plastic agent may be melted and the pad removed or replaced. Such facility of replacement has been heretofore unknown in the application of a conventional pad.

In the search for a suitable pad attempts have been made to utilize rubber, but pads of this material when applied to metal surfaces, similar to those surrounding an aperture, have caused the metal to tarnish and the pad to fit imperfectly or to stick.

It is therefore an object of this invention to

2

provide a new and improved pad which will overcome the above named difficulties, fulfill the requirements specified, and have the characteristics set forth as desirable.

Another object of this invention is to provide an improved resilient stop pad for the stops of an instrument which will readily adapt itself to the contour of an aperture with a minimum of applied pressure.

Still another object of this invention is to provide an improved resilient pad which will not tarnish a metal surface to which it is applied.

A further object is to provide a new and improved closure pad for the apertures of wind instruments having a resilient body and glossy yet flexible surface which effectively stops the aperture without unduly deadening the tone of the instrument.

A still further object is to provide a pad which does not warp, loosen, or alter its shape after long periods of use.

Another object of this invention is to provide a new and improved closure pad for the apertures of wind instruments having the desired

character described which is simple in design, positive in action, readily and economically manufactured and easy to install, it being also an object to provide a readily adaptable pad having a resilient body portion, a rigid backing structure and a smooth non-damping operating surface.

This invention also has for an object the improvement of prior art devices of similar character.

Other objects and advantages will appear and be brought out more fully in the following specification, reference being had to the accompanying drawings, wherein:

Figure 1 is a perspective view of a pad embodying my invention.

Figure 2 is a perspective view of a sheet stock of raw material from which my pad may be cut.

Figure 3 is a sectional view of my improved pad in place within an instrument key pad holder.

Figure 4 is a fragmentary longitudinal sectional view of an instrument utilizing my improved pad.

Figure 5 is a view similar to Figure 4 showing the use of my pad upon a different form of instrument.

Figure 6 is a perspective view of a modified form of my improved pad.

Figure 7 is a perspective view of a still further modified form of pad.

Referring more particularly to the drawings I show a pad generally designated by the reference numeral 10 comprising a disc element 11 of a sponge rubber-like material and a relatively rigid disc element 12 of the same diameter as the rubber-like disc element firmly secured together in axial alignment at their adjacent faces.

The rubber-like disc element 11 may be formed of a relatively closed-cell sponge rubber material having at least one molded face 13. The disc elements 11 and 12 may be formed in various manners but I prefer to cut the rubber-like disc element 11 from a relatively large flat sheet 20 of sponge rubber, though other types of rubber or resilient material which may be similarly handled may likewise be employed. The materials comprising the disc elements may be initially joined together by a suitable cementing operation and the discs subsequently cut from the combined sheets. Under some circumstances, however, the elements may be cemented together after being cut or punched out.

Before cutting or punching out the rubber-like discs, I prefer to coat the sheet 20 upon the side corresponding to face 13 with a layer 21 of material forming a tough, hard surfaced, but flexible coating. When the coating has been dried and cured it completes the composite stock sheet from which the discs 10 are cut. Although various types of materials are suitable for application to the molded surface to provide a facing or skin of the desired consistency, certain solutions of plasticised polyvinyl resins and a cement-like coating, known commercially as hard-drying rubber, cement, resin, or the like have been found to be especially advantageous. These and similar materials adhere tenaciously to the pad and dry to a relatively hard surface consistency which has the property of reflecting sound waves rather than absorbing or damping them. When the stop provided with a pad of this construction is closed, the tone of the instruments will remain true.

Toughness of the surface thus formed provides for long wear and the inherent flexibility permits the material of the disc element to press the surface into close contact with the edge of the stop aperture, making a true closure for every successive application of the pad to the stop.

Under some circumstances, a raw edge 22 may be left upon the rubber-like discs thereby preserving a uniform resiliency over the entire area of the face 13 whether at a central or peripheral portion. Aeration of the edges is thereby facilitated, decreasing the tendency of the sponge to rot without increasing the rigidity of the side walls.

As shown, the disc 10 comprising the combined disc elements 11 and 12 is adapted to be used on a musical instrument 16 in a manner permitting the molded face 13 to be applied to a stop 15.

In the many kinds of instruments on which the pad may be used various forms of pad retainers 26 are provided, such for example as a key 27. The key is normally pressed to a closed position over the stop 15 by any resilient means such as a spring 29, the key being mounted for rotation upon a pivot 30. Tension of the spring in closed position of the key is intentionally slight to permit easy fingering of the instrument. The pad should rapidly and thoroughly adhere to the contour of the rim orifice under slight pressure.

In some instruments, particularly saxophones and the like, the base notes are formed by orifices

having a diameter as large as two inches or more. In such instruments the tension of the spring is customarily relatively great so as to force an adequate closure. Relatively great tension of the spring often results in difficult and strenuous fingering operations.

Figure 5 illustrates a key 26 applied to an instrument 16 wherein the rim of the stop aperture has a raised edge 35 upon which the outer portion of the pad is pressed.

Furthermore, especially in apertures of large diameter, stop pads are generally provided with a sounding member such as a central, flat, metal disc applied to the central part of the under side of the pad to act as a resonator and prevent damping of the resonance of the instrument over the large area covered by the pad. Such metal resonators are not necessary in my device because of the resonating surface of the layer 21 having the flexible, yet hard, glossy surface described on the operating face of the disc.

In my pads, especially where used on relatively large openings, the backing strip or disc element 12 is particularly advantageous. This disc element can be made of metal, wood, plastic or equivalent stiff material of a thickness approximately equal to that of the rubber-like disc element 11. A pad having a total thickness of $\frac{1}{8}$ of an inch for example may be made up of a stiffening disc element having a thickness of $\frac{1}{16}$ of an inch and a rubber-like disc element of equal thickness. This construction tends to present a more uniformly flat surface 13 and avoids both the necessity of a stiff spring and the break down of the cell walls of the sponge rubber brought about by undue pressure.

In using pads having my construction the pad may be merely pressed into place in the retainer and secured therein as by glue, shellac or the like. Shellac is especially suitable in that it may be dissolved by slight heat applied to the retainer for removal or replacement of the pad but dries under ordinary temperatures to hold the pad within the retainer.

I have found that the materials specifically referred to herein are best applied to the sheet 20 by spraying or brushing and then by curing at a temperature of approximately 115° F. for approximately ten minutes. Such curing produces a desired glazed film upon the surface of the sponge material, preventing absorption or deadening of sound by the pad and preventing tarnish. It should be noted that the problem of resonance absorption by pads of relatively smaller diameters has not been met by pads heretofore used, and that such absorption is deemed inevitable because of the difficulty of applying a metal disc to the small otherwise sound-absorbent structure. Due to the glossy surface of materials such as hard-drying rubber, cement, resin, or the like, when cured as described, apertures of any size bore may be effectively stopped without substantial loss of resonance whether the aperture is very large or very small.

By way of example, I have determined that a layer of surfacing material of a thickness of approximately .003 to .005 of an inch is suitable.

In the embodiment of Figure 6 I show a disc 10', comprising a single uniform body of closed cell sponge rubber 30, having a lower face 13' of molded sponge material coated with cured Vulcabond or the like. This preferred embodiment is preferably $\frac{1}{8}$ of an inch thick and is used without rigid support and may be directly

cut from a suitably treated sheet of closed cell sponge rubber of relatively high density and small cell structure. In this form the disc may be applied directly to a stop receptacle and is particularly suitable for use in closing apertures of small bore.

Another form of pad 10" is illustrated in Figure 7, wherein one face of a rubber-like disc 11' is joined to a rigid disc 12'. The pad 10" is formed with an axial opening 31 extending from top to bottom of the pad. This form of pad is adapted for use in instruments having a primary as well as a secondary closure or aperture over a single stop. The rigid upper disc 12' tends to preserve the form of the annular pad 10". If desired, a second layer of rubber material having a superimposed film of the herein described surfacing material may be applied to the top face of the rigid disc 12' so as to furnish a pad having two effective faces for the stoppage of the full tone orifice and the half tone orifice respectively. It is further obvious that the embodiment of Figure 7 may comprise a single apertured disc of uniform sponge rubber construction without utilizing a rigid disc in association therewith.

While I have herein described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

Having thus described my invention, what I claim and desire to secure by Letters Patent is:

1. In combination with a wind instrument having a succession of stops, a sponge rubber pad adapted for closing said stops, said pad comprising a discoidal cellular body having edges of closed cellular structure and flat faces, and a uniform film of hard rubber cement coating one of said flat faces.

5 2. A pad for stopping the orifices in a musical instrument comprising a sponge rubber disc having at least one smooth face, a relatively rigid disc of substantially the same diameter and thickness as the sponge rubber disc, said rigid disc being attached to a face of the sponge rubber disc other than said smooth face and a glazed film of adhesive attached to said smooth face, said adhesive comprising a hardened plastic material having tough, hard sound-reflecting and flexible characteristics.

10 3. A pad for stopping the orifices in a musical instrument comprising a sponge rubber disc having at least one smooth face, a relatively rigid disc of substantially the same diameter and thickness of the sponge rubber disc, said rigid disc being attached to a face of said sponge rubber disc other than said smooth face, and a film of smooth surfaced material of the nature of 15 hard surfaced cementitious resin adhering to said smooth face, said pad having an axial bore there-through.

15 4. In a substantially discoidal stop pad for wind instruments comprising a body of closed-cell sponge rubber and a smooth surface formed on at least one side thereof adapted when mounted in said wind instrument to selectively close a sound selecting aperture, the improvement comprising a thin, yieldable film on said 20 smooth side of glossy, hard-surfaced resinous material.
